UNITED STATES PATENT OFFICE.

SELVIYOR A. SWANSON, OF CHICAGO, ILLINOIS, ASSIGNOR OF ONE-THIRD TO SAMUEL S. PORTER AND ONE-THIRD TO FREDERICK S. BRASOR, OF MARIETTA, OHIO.

AUTOMATIC PIANO-PLAYER.

No. 904,284.

Specification of Letters Patent.

Patented Nov. 17, 1908.

Application filed February 11, 1907. Serial No. 356,851.

To all whom it may concern:

Be it known that I, SELVIYOR A. SWANSON, a citizen of the United States, residing at Chicago, in the county of Cook and State of Illinois, have invented certain new and useful Improvements in Automatic Piano-Players, of which the following is a specification, reference being had therein to the accompanying drawing.

10 My invention relates to pianos, organs or other musical instruments which are adapted to be played manually or automatically and has as its object to simplify and cheapen the construction, to lessen the space occupied by

15 the pneumatics and to improve generally the operation and durability of such instruments.

The invention comprises in its specific arrangement a key table and the ordinary piano action, together with tuned strings and a sounding board, and a plurality of striking pneumatics controlled automatically by a tracker board and note sheet and arranged in alternate relation, one above the other so that, for example, the operating lever of the pneumatic which operates the G string hammer in the treble is located above and slightly staggered with relation to the operating lever of the pneumatic operating the A string hammer. The pumping bellows is utilized in connection with the main wind chest and reservoir bellows to operate the mechanically driven note sheet rolls as is usual, and atmospheric pressure is used to counteract the suction in primaries and to operate through the usual puff pneumatics the main valves which permit suction to act on the main striking pneumatics. The motor is suitably governed so that it does not travel any faster with increased or any slower with decreased pressure.

Heretofore, instruments of this character have been so designed, with their pneumatics horizontally arranged one above the other in tiers, that it was impossible to make a thoroughly reliable automatic player in combination with a manual player, the wippen abstracts being so numerous and in some instances of such length as to render them unfit for practical use, and so complicating the mechanism as to require experienced and high priced workmen to attend to repairs even of a minor nature.

My invention is designed to obviate these difficulties and will be better understood

from the following description when taken in connection with the accompanying drawings, in which—

Figure 1 is a vertical transverse sectional view of a piano including my improvement, 60 and Fig. 2 is a partial sectional front elevation of a piano embodying the invention with the action represented diagrammatically and certain parts of the casing removed.

Referring now to Fig. 1 in the drawings, 1 designates the pedals, to be more fully hereinafter described, which operate the air pumping bellows 2 in this instance held to the main wind chest 3 which is connected to the ordinary reservoir bellows 4. The reservoir bellows has an automatic valved air current regulator 5 and attached to the wind chest 3 is the music sheet motor valve chest 6. All of these parts 2 to 6 are old and well known in the art and need no further description as they relate merely to the air pumping mechanism which is necessary in all such pneumatic constructions. The key table 7 is of the usual construction and has pivoted thereto the keys 8 connected by the abstracts 9 to the wippons 10 which operate the action hammers 11, through the well known piano mechanism, so as to strike the strings 12. These strings are carried upon the usual metallic frame 13 supported by the frame 14 and have located behind them a sounding board 15. Each wippen 10 is provided with an adjusting rod 16 adapted to be engaged by the jacks 17 pivotally secured upon a longitudinal supporting strip 18. Each striking pneumatic 19 is provided with a pivoted link 20 secured at one end thereof, and this link is connected to its respective jack 17 in any suitable manner so that when the pneumatic is collapsed it may tilt the jack upon its pivot and so operate the wippen to cause the hammer to strike the string. The striking pneumatics 19 are arranged one above the other and have their links 20 arranged in staggered relation so that they may be located within the casing and occupy as small a space as is consistent with proper operation. Each pneumatic is supplied with a primary and in practice all of the primaries are made in two sections or tiers, each tier comprising an individual unit with a plurality of primaries therein.

The tracker board 21 is of the usual construction and has tubes 22 leading from each

opening which tubes communicate with their respective primaries 23 so as to control the action of the exhaust for the pneumatics 19. Each primary has an opening 24 governed by a vertical reciprocating valve 25 which normally closes and prevents access from the exhaust chamber 26 to the opening 24 which communicates with the pneumatics. This valve is provided with a vertical rod rigidly connected thereto at one end and at the other to a puff pneumatic 27 bridged across the mouth of a channel 28 communicating with the tube 22. A vent 29 communicates with the tube 22 and the chamber 26 so that when the valve is in a normal position there is sufficient leakage through the vent 29 to equalize the pressure in the tube 22 with that in the chamber 26. In Fig. 2 I have shown a number of tubes leading from the tracker board 21 but in Fig. 1 I have shown only one of said tubes and have indicated it as passing through the upper primary, but with no communication therewith, and adapted to operate the lower primary. This is done to facilitate the reading of the drawing but it will be understood that there is no connection of any tube 22 with more than one primary.

I have not illustrated any connection from the reservoir bellows 4 to the motor mechanism but this is a feature which does not play any part in my invention except as an operating connection of some sort must be provided although not necessary to illustrate and therefor not shown or described herein.

When an opening in the note sheet 31 passes over an opening in the tracker board 21 atmospheric pressure from the outside passes down the pipe 22 to its respective pneumatic where it raises the diaphragm 27 thus operating the valve 25 to open the channel 24 and allowing the vacuum in the chamber 26 to deflate the pneumatic 19, operate the jack 17 which communicates its motion through the adjusting rod 16 to the wippen 10 and the striking hammer of the action. Instead of utilizing the jacks to operate the wippons of a piano action I may and do employ them, as well for controlling a reed or pipe action for pneumatic playing organs, and I contemplate such use as within the scope of the appended claims.

In pianos and organs of the class just described it is necessary to utilize pumping pedals for operating the pumping bellows 2. Such pedals are usually cumbersome and unsightly as well as in the way when the device is not in use. A pair of pedals which may be folded in such a way that they will not obstruct or interfere with the use of the forte and pianissimo pedals 32 which are of the usual type and in the usual position, are illustrated herein. The pumping pedals each comprise a supporting lever 33 pivoted at 34 to the underneath side of the

piano, and having at its outer extremity a lug or turn-up lip 35 to which is pivoted the foot piece 36 of the usual construction. Connected to this foot piece is a connecting link 37 removably engaging at its upper end a bell crank lever having fulcrum at 39 in a bearing carried by the main wind chest 3. The end of the bell crank lever opposite to that which is engaged by the connecting link 37 is provided with a friction roller 40 bearing against a wear plate 41 which has a cam face, and which is secured to the main pumping bellows 2. This cam face together with the action given the bell crank lever gives a differential or multiplied movement. By disconnecting the link 37 and folding it down alongside the foot piece 36 and by lowering the foot piece and the link so that they rest upon the lever 33 the entire pedal may be folded laterally beneath the piano frame thereby giving clear access to the piano pedals.

It will be seen that by arranging the pneumatics vertically one above the other and staggering their operating links 20 I am enabled to gain a great deal of space which has been heretofore taken up by the pneumatics and their primaries when placed horizontally and in tiers. By my construction the action is not only cleared but a more positive operation is assured and a great many parts are dispensed with which were liable to disarrangement such as the wippen operating rods which were connected to the pneumatics and were in some instances extremely long and necessarily very light in construction.

Although I have shown and described a simple embodiment of my invention I do not wish to be limited to the special detailed construction illustrated as I might change the construction in practice and resort to many modifications without departing from the scope and spirit of the invention, as defined in the appended claims.

Having thus described my invention, what I claim, and desire to secure by Letters Patent, is:—

1. In a musical instrument, the combination with a plurality of tuned strings and a player action therefor comprising wippons and other operating mechanism, of a plurality of pneumatics arranged in front of said player action, each being substantially parallel to said strings, operating connections between said pneumatics and the wippons of said player action, and means for controlling the pneumatics.

2. In a musical instrument, the combination with a plurality of strings and operating devices therefor comprising wippons and other operating mechanism, of a plurality of pneumatics arranged in front of said operating levers, each being substantially parallel to said strings, and operating connections be-

tween said levers and the wippens of the operating connection devices.

3. In a musical instrument, the combination with a plurality of strings, strikers therefor and wippens for said strikers, of pneumatics for operating said strikers and having staggered operating levers, each of said pneumatics being substantially parallel to said strings, a plurality of jacks connected with said operating levers, operating connections between said jacks and the wippens, and controlling means for the pneumatics.

4. In a musical instrument, the combination with a plurality of strings, strikers therefor and wippens for said strikers, of vertical pneumatics for operating said strikers arranged one above the other in front of the strikers and having staggered operating levers, a plurality of jacks between the wippens and the operating levers and connected to the latter, operating connections between the jacks and the wippens, and a tracker board and note sheet for controlling the pneumatics.

5. In a musical instrument, the combination with a plurality of tuned strings,

strikers therefor and wippens for said strikers, of a plurality of vertical pneumatics arranged one above the other in banks and having staggered operating levers, jacks connected to said levers, adjustable connections between the jacks and said wippens, primaries for said pneumatics, and a tracker board and note sheet for controlling said pneumatics through the primaries.

6. In a musical instrument, the combination with tuned strings and a player action therefor comprising wippens and other operating mechanism, of a plurality of pneumatics arranged in tiers one above the other, operating arms connected to the pneumatics, bell crank levers connected to the wippens, and connections between the arms and the bell crank levers arranged substantially parallel to the wippens.

In testimony whereof I affix my signature in presence of two witnesses.

SELVIYOR A. SWANSON.
